UNITED STATES PATENT OFFICE.

FREDERIC L. WARD, OF OXFORD, MICHIGAN.

APPARATUS FOR GRADING MATERIAL.

Application filed August 8, 1927. Serial No. 211,558.

This invention relates to apparatus for grading material and more particularly to a traveling grizzly screen for separating sand and gravel.

- 5 The invention has as one of its objects to provide a continuously operating sand and gravel separating machine of a construction wherein the materials can be elevated and screened at one operation. This apparatus finds particular utility in hydraulic excavating systems of the type designed for the removal of sand and gravel from sub-aqueous deposits where it is not only desirable to screen the gravel but elevate it as well.
- 10 15 It is a further object to obtain a construction in which the wear on the screen cloth is reduced to a minimum as the gravel is carried by the screen and does not slide on its surface.
- 20 The invention further contemplates the provision of mechanical means for vibrating the screen without the use of additional power.
- 25 The invention also contemplates numerous novel details of construction and has also as its objects to simplify, render more efficient and improve generally apparatus of this character.
- 30 The above objects and novel details of construction of the invention will be made more apparent as this description proceeds, especially when considered in connection with the accompanying drawings wherein—

Figure 1 is a side elevation of the machine embodying my invention;

Figure 2 is a plan view thereof;

Figure 3 is an end elevation thereof; and

Figure 4 is a detailed perspective view of the screen cloth and the connection therewith of the chain shafts.

Referring now more particularly to the drawings wherein like reference characters indicate like parts, it will be noted that there is illustrated a frame 10 inclined within the angle of friction and bent upwardly intermediate the ends thereof forming a platform or table 11 constituting a support for the upper tracks 12. Depending from and extending substantially parallel to the frame 10 is a second frame 13 secured at the opposite ends thereof to the frame 10 by means of the tie members 14 and constituting a support for the lower tracks 12'. Extending transversely of and journaled in suitable bracket bearings 15, secured upon opposite sides of the frame 10 adjacent the rear end

thereof is a shaft 16 carrying relatively large sprocket wheels 17 and 18. A second shaft 19 is mounted upon the frame adjacent the forward end thereof and carries the sprocket wheels 20 and 21 arranged in direct alignment with the sprockets 17 and 18. As shown the shaft 19 is journaled in bearings 22 slidably mounted upon the ways 23 formed on the brackets 24 which are secured on opposite sides of the frame 10. For positively feeding the shaft 19 longitudinally of the frame a pair of screws 25 threadedly extend through the upright portions 26 of the brackets 24 and engage the bearings 22. Thus it will be apparent that the longitudinal distance between the shafts 16 and 19 is variable, enabling the device to be used as a conveyor or picking table.

The sand and gravel separating member comprises an endless screen cloth 27 divided into a plurality of uniform sections 20' which are secured to an endless bar link chain 29 carried by the sprockets. The pivots 30 for the links of the chain extend transversely of the screen and are provided upon the opposite ends thereof with the flange rollers 31 engageable with the upper and lower tracks 12 and 12'. In order to provide a flexible screen so that the latter will conform to the curvature of the sprockets every other strand of each section is looped around the pivots 30 as indicated at 28.

In order to insure a more efficient screening of the materials discharged upon the screen the latter is vibrated. For accomplishing this result a plurality of longitudinally spaced blocks 32 are secured to the upper tracks 12. As shown, these blocks are inclined upwardly from the tracks in the direction of travel and are provided with a substantially straight side 33. With such an arrangement it is to be noted that the screen is efficiently vibrated irrespective of the load thereon, without the use of additional driving means. In prior sand machines using a separate prime mover for vibrating the screen a serious disadvantage has been commonly experienced in the necessity of providing a surplus of available power for vibrating the screen when the latter is overloaded. In the present construction, however, as noted above, the weight of the material as well as the apparatus is utilized to vibrate the screen and the use of a separate prime mover for this purpose is eliminated.

Moreover, with the herein described apparatus, the vibrations of the screen are of the same amplitude irrespective of the load on the screen, a very desirable feature in apparatus of this character as the life of the same is greatly enhanced.

For rotating the sprockets and consequently the bar link chain, a gear reducing mechanism 34 is provided, which may be 10 driven by any suitable prime mover and is connected by means of the chain 35 to a sprocket 37 mounted upon one end of the shaft 16.

The operation of the apparatus will no 15 doubt be readily apparent from the foregoing description, it being understood that the aggregate is discharged upon the screen at the lower end thereof and is conveyed upwardly by the screen in the direction indicated by the arrow in Figure 1 and due to 20 the vibration of the screen as set forth above, the fines will drift through the mesh into a suitable by-pass chute 38 and be discharged at the side between the screening surfaces. 25 The oversize being carried upwardly by the screen and discharged over the end thereof into any suitable container such for example a stone crusher.

Thus from the foregoing, it will be readily 30 apparent that I have provided a traveling grizzly screen inclined against the action of gravity and within the angle of friction so that the screen will not only function as a conveyor for elevating the rejected material 35 to facilitate its handling but will more efficiently screen the material.

What I claim as my invention is:

1. In a machine for grading materials, a 40 frame, tracks upon said frame, sprockets carried by said frame adjacent the opposite ends thereof, a bar link chain carried by said sprockets, the pivots for the links of said chain having rollers upon the opposite ends thereof engageable with said tracks, a screen carried by said chain and secured to the pivots aforesaid, and projections upon said tracks engageable with said rollers to vibrate said screen.

2. In a machine for grading materials, a 50 frame bent upwardly intermediate the ends thereof forming a platform, tracks upon said platform, sprockets journaled upon opposite sides of and adjacent the opposite ends of said frame, a bar link chain carried 55 by the sprockets, the pivots for the links of said chain having the opposite ends thereof projecting beyond the sprockets and provided with rollers engageable with said tracks, a screen comprising a plurality of 60 sections having the opposite ends of each section looped around and secured to the pivots aforesaid, and means upon said tracks

in the path of said rollers for vibrating said screen.

3. In a machine for grading materials, 65 the combination with a frame, of a chain movable relative to said frame, and a screen comprising a series of sections disposed between the links of said chain and having the end portions of certain strands encircling 70 and connected to the link pivots of the chain.

4. In a machine for grading materials, the combination with a frame, of a bar link chain carried by the frame, and a sectional 75 screen having the strands thereof encircling the pivots for the chain intermediate the links thereof.

5. In a machine for grading materials, the combination of a screen comprising a series 80 of sections having strands terminating in looped end portions, and a chain including a series of pivots arranged to extend through the loops aforesaid for hingedly connecting adjacent sections of the screen. 85

6. In a machine for grading materials, the combination of a sectional screen, alternate strands of adjacent sections of the screen terminating in looped portions, and a bar 90 extending through the said looped portions for hingedly connecting the said sections.

7. In a machine for grading material, the combination of a sectional screen, alternate strands of adjacent sections of said screen terminating in looped portions, and a bar link chain for actuating said screen having the pivots for the opposite links arranged to project through said loops for hingedly connecting the sections.

8. In a machine for grading materials, the 100 combination with a frame having track portions, of a sectional screen carried by the frame, and a bar link chain having the pivots thereof extending transversely of the screen and arranged to pivotally connect the sections thereof to form a continuous screen, the pivots aforesaid also arranged to project beyond the opposite sides of the screen and engage the track portions aforesaid. 105

9. In a machine for grading materials, the 110 combination with a frame having spaced track portions formed with irregular surfaces, of a sectional screen carried by the frame, and a bar link chain having the pivots thereof extending transversely of the 115 screen and arranged to pivotally connect the sections of the latter to form a continuous screening surface, the pivots aforesaid being of sufficient length to project beyond the opposite sides of the screen and engage the 120 irregular surfaces upon the tracks for vibrating the screen.

In testimony whereof I affix my signature.
FREDERIC L. WARD.
